[57] CLAIM

The ornamental design for a wedge lock for a sliding panel, substantially as shown.

DESCRIPTION

FIG. 1 is a front perspective view of a wedge lock for a sliding panel showing my new design;

FIG. 2 is a front perspective view of a second embodiment of FIG. 1;

FIG. 3 is a top plan view of both embodiments;

FIG. 4 is an end elevational view of both embodiments;

FIG. 5 is a bottom plan view of FIG. 2;

FIG. 6 is a bottom plan view of FIG. 1.

FIG. 1

FIG. 2

FIG. 3

FIG. 4

FIG. 5

FIG. 6
